UNITED STATES PATENT OFFICE.

BERNHARD VOLKMAR, OF NEW YORK, N. Y., ASSIGNOR TO THE ACME
AUTO-METER COMPANY, OF NEW YORK, N. Y.

ODOMETER.

No. 813,846.

Specification of Letters Patent.

Patented Feb. 27, 1906.

Application filed September 6, 1905. Serial No. 277,212.

To all whom it may concern:

Be it known that I, BERNHARD VOLKMAR, a citizen of the United States, and a resident of the city of New York, borough of the Bronx, in the county and State of New York, have invented a new and Improved Odometer, of which the following is a full, clear, and exact description.

The purpose of the invention is to provide an odometer of very simple, durable, and economic construction, wherein a series of registering-disks and a series of recording-disks are mounted upon the same carrying-shafts, the recording-disks being so arranged that they will show the aggregate amount of miles traveled during a number of trips—for example, the registering-disks being adapted to show the number of miles made during each trip, and the arrangement of the latter disks is such that all of them may be quickly and conveniently turned back to zero at any time by turning the carrying-shaft and without changing the position of the recording-disks.

The invention consists in the novel construction and combination of the several parts, as will be hereinafter fully set forth, and pointed out in the claims.

Reference is to be had to the accompanying drawings, forming a part of this specification, in which similar characters of reference indicate corresponding parts in all the figures.

Figure 1 is a front elevation of the improved device. Fig. 2 is a vertical longitudinal section through the casing of the device and a partial vertical section and side elevation of the interior mechanism. Fig. 3 is a vertical transverse section taken practically on the line 3 3 of Fig. 2. Fig. 4 is a side elevation of a recording-disk and a section of the carrying-shaft, the section being taken substantially on the line 4 4 of Fig. 2. Fig. 5 is a detail sectional view of a portion of one of the disks, a plan view of the actuating-pin for the disk, and a transverse section through the spring-arm carrying the pin. Fig. 6 is a section taken substantially on the line 6 6 of Fig. 2, the section being through a spacing-collar of a registering-disk and the carrying-shaft, the shifting sleeve for the disk being shown in end view. Fig. 7 is a vertical transverse section taken practically on the line 7 7 of Fig. 2; and Fig. 8 is a transverse section through the actuating spring-arm for a disk,

either registering or recording, the section being taken practically on the line 8 8 of Fig. 7.

A represents a box-casing having suitable lugs 10 for attachment to a vehicle and a glass pane 11 at the top, through which a plate 12 is visible, having two series of openings 13 and 13^a therein, a series being at each side of the center of the plate, as shown in Fig. 2. At the central longitudinal portion of the casing A a bar 14 is located near the bottom of the said casing, which bar extends from end to end of the casing and is attached thereto, being provided at its ends with upwardly-extending arms 15 and a central arm 16, having an enlarged upper end 16^a. A shaft B is journaled in the said arms 15 and 16, having end as well as rotary movement. The right-hand end of the shaft B extends out through an opening 17 in the right-hand side of the casing, as is shown in Fig. 2, and is secured to a knob 18, having a chamber 19 in its inner face, in which chamber a spring 20 is located, coiled around the carrying-shaft B and having bearing against the right-hand arm 15 of the bar 14, as is also shown in Fig. 2.

A series of registering-disks C is loosely mounted on the shaft B, one below each opening 13, and the said disks C are provided with peripheral figures reading from "0" to "9," inclusive. Each disk C is also provided with a central bore 21, of sufficient size to receive and turn loosely around a sleeve 22, as is shown in Fig. 2, and the sleeves 22 of all of the disks are in frictional engagement with the carrying-shaft B. Each sleeve 22 is provided with a finger 23 at its forward end, extending out from the periphery of the sleeve, as is shown in Figs. 2 and 6, and pins 24 and 24^a are passed through the carrying-shaft B, one in front of and the other to the rear of each sleeve 22. When the shaft B is in its normal position, (shown in Fig. 2,) the rear pins 24 hold the sleeves 22 in such position that their fingers 23 are removed some distance from the outer side faces of the disks C, as is also shown in Fig. 2. The disks C are spaced from each other by collars 25, loosely mounted upon the carrying-shaft B, which collars are sufficiently large at their inner end portions to permit the fingers 23 of the sleeves 22 to freely turn therein, and a simple collar 26 spaces the innermost disk C from the central arm 16.

At the outer side face of each registering-disk C a series of openings 27 is made, corresponding in number to the number of figures upon the periphery of a disk, an opening 27 being immediately below each figure upon a disk, and one side of each opening is provided with an inclined outer wall portion 27^a, as illustrated in Figs. 4 and 5, said inclination being provided for a purpose to be herein-after set forth.

A pin 28 is made to project from the outer face of each disk C adjacent to its bore 21, the said pins being in the path of the fingers 23 of the sleeves 22 when the shaft B is pushed inward, as when said shaft is carried inward the outer pins 24^a on the shaft will carry the sleeves 22 in the same direction, so that as the shaft B is turned while at its inner position the sleeves 22 will be turned also, and the fingers 23 of the sleeves upon striking the pins 28 will simultaneously turn all of the disks C, and said disks C are thus turned when they are to be brought to their initial position, presenting zero at the openings 13, as will be hereinafter more particularly described.

A spring latch-arm C' is located at the inner side of each disk C, as is shown in Figs. 2 and 7. Each spring latch-arm consists of a ring-like body 29, sufficiently large to loosely receive a spacing-collar 25, which body has a head-piece 30 integral therewith secured to the disk to which the latch belongs and a foot-section 31, that extends to the edge of the disk, as is particularly shown in Fig. 7. The foot-section 31 of a spring-latch has a stud 32 extending inward therefrom or in direction of the opposing disk, and the studs on the latch-arms of one disk are adapted to enter the openings 27 in an opposing disk to turn the same at a proper time, and at the outer end of the foot-section 31 of each spring-latch arm C' the foot is bent upon itself so as to extend out at an inclination in direction of an opposing disk C, forming at the foot-section of each latch-arm C' an inclined offset toe 33, as is shown in Figs. 2, 5, 7, and 8. After a disk C has made one revolution the foot-section of its latch will engage with a spur 34, extending upward from the bar 14, a spur being provided for each latch, and as the toe 33 of the latch engages a spur 34 the foot of the latch will be sprung outward, causing the spur on the latch to enter an opening 27 in the opposing disk to turn the same one figure, and as soon as the foot of the spring-latch has passed the spur with which it engages the said latch, owing to its resiliency, will spring back against the disk, assuming its normal position and withdrawing the stud from engagement with the disk which it had just moved. The bevel 27^a in the walls of the opening 27 facilitates the quick entry of the stud 32 into said opening.

65 A ratchet-wheel C² is loosely mounted upon

the right-hand end portion of the carrying-shaft B, separated from the first registering-disk C by a collar 35, corresponding to the collars 25, and in connection with the ratchet C² a spring latch-arm C' is employed of the same construction as those which have been described. The said spring latch-arm for the ratchet-wheel is adapted to give movement at the proper time to the initial or units disk C by reason of the stud 32 of the said latch-arm entering an opening 27 in the said first disk C, as is shown in Fig. 2. The latch-arm for the ratchet-wheel C² is attached to the offset 36 from the periphery of the wheel, as is illustrated in Figs. 2 and 3, and the latch-arm for the ratchet-wheel C² is operated upon by a spur 34^a, corresponding to the spurs 34, heretofore mentioned, being carried by the same bar 14. The ratchet-wheel C² is provided with a pawl 37, which prevents the wheel slipping in the wrong direction, said pawl being mounted on the right-hand arm 15 of the spur-carrying bar 14.

A counter-shaft 38 is mounted in suitable bearings in the casing A below and to one side of the bar 14, and at the right-hand end of the counter-shaft 38 an eccentric 39 is secured to said shaft, as is shown best in Fig. 3, which eccentric receives a collar 40 of a dog 41, which engages with the teeth of the ratchet-wheel C² to turn said wheel at predetermined intervals. The dog 41 may be attached to the eccentric 39 in any approved manner—as, for example, the eccentric may be provided with a peripheral groove, and a set-screw 42 may be passed through the collar into said groove, as is shown in Fig. 3. A spring 43 holds the dog down to its work. The counter-shaft 38 is provided with a worm-wheel 44, which meshes with a worm 45 upon a shaft 46, and this shaft is led out from the casing through a suitable bearing to a connection with the axle of the vehicle or other factor from which speed and power is to be taken.

It will be observed that as the ratchet-wheel C² is turned to bring the post 32 of its latch-arm C' opposite an opening 27 in the initial registering-disk C the said post will enter said opening and the disk will turn with the ratchet-wheel until the foot portion of the latch-arm C' has passed its spur 34^a, and after the first disk C has made one revolution the spur of its latch-arm C' will be forced by reason of the foot of the latch-arm riding on its spur 34 into the opening 27 in the next recording-disk to turn it in the same manner as has been described with reference to the first disk C, and this operation is repeated until all of the disks have been turned to indicate at the openings 13 in the plate 12 the number of miles traveled—as, for example, "199," as shown in Fig. 1—and the latch-arms C', as shown in Fig. 2, and the first, second, and third disks C occupy such positions relative

to their controlling-spurs on the bar 14 that at the next action of the ratchet-wheel C² the figure on the first disk will be changed from "9" to "0", the figure on the second disk 5 from "9" to "0," and the figure "1" on the third disk will be changed to "2," making the reading at such time "200." Supposing the end of the journey to have been reached and it is desired to carry all of the registering-disks C back to zero, this is quickly done by simply pushing in the shaft B, as has been described, until the fingers 23 of the sleeves 22 are brought in the path of the pins 28 on the disks C, whereupon the said shaft is turned 10 until the foot portions of all of the latch-arms C' are in engagement with the rear faces of the other controlling-spurs 34 and 34^a, and at such time a cipher will appear at each of the openings 13.

20 To the left of the casing a series of recording-disks D are loosely mounted on the shaft B, and each recording-disk has figures on its periphery reading from "0" to "9." On the said shaft B adjacent to the first recording-disk a ratchet-wheel D' is loosely mounted, provided with a latch-arm D², and each of the recording-disks is likewise provided with a latch-arm D², all of said latch-arms D² being alike in construction to the construction 25 of the latch-arms C', heretofore mentioned. The ratchet-wheel D' is operated through the medium of a dog 47, corresponding to the dog 41 for the registering-disks C, and this dog 47 is mounted upon an eccentric 48 at 30 the inner end of the line-shaft 38, as is shown in Fig. 2, the eccentric 48 being a duplicate of the eccentric 39. Each recording-disk D is provided with a series of openings 49 in its side, corresponding to the openings 27 in the 35 registering-disks C. A recording-disk D is located below each opening of the series 13^a in the plate 12, so that the figures on said disks may be read at said openings, and the operation of the recording-disks is identical 40 with the operation of the registering-disks, the foot portion of each spring latch-arm D² being provided with a controlling-spur 50, carried by the bar 14, as is illustrated in Fig. 2. The disks are spaced one from the other, 45 preferably by means of hubs 51, located at one side face. The recording-disks are adapted to show the aggregate of miles traveled in a number of trips, while the registering-disks are adapted to record simply the 50 number of miles traveled at each trip. Consequently it is not necessary to provide the means shown in connection with the registering-disks to turn the recording-disks back; but such means may be employed or other 55 means may be utilized for bringing the recording-disks to zero when desired. As shown, it will be observed that the operation of the shaft B to set the registering-disks has no influence whatsoever upon the recording- 60 disks.

Having thus described my invention, I claim as new and desire to secure by Letters Patent—

1. In odometers, a casing, a carrying-shaft mounted for end and rotary movement in the casing, a set of registering-disks and a set of recording-disks loosely mounted on the said shaft, one set of disks being independent of the other and each disk in a set being independent of each other, each disk of both sets being provided with series of apertures in one of its faces, a ratchet-wheel loosely mounted on the said carrying-shaft adjacent to the initial disk of each set, spring latch-arms secured at one end to the face of each disk opposite that containing the apertures, a similar arm being similarly connected with each ratchet-wheel, each of the said latch-arms having a bevel foot-section formed at its free end, and posts on said foot-sections adapted to enter apertures in opposing disks, fixed spurs located in the path of the foot-sections of the said latch-arms, a line-shaft, means for driving the line-shaft, and independent dogs carried by said line-shaft, engaging the said ratchet-wheels.

2. In odometers, a casing, a carrying-shaft mounted for end and for rotary movement in the casing, a set of registering-disks and a set of recording-disks loosely mounted on the said shaft, one set of disks being independent of the other and each disk in a set being independent of each other, each disk of both sets being provided with series of apertures in one of its faces, a ratchet-wheel loosely mounted on said carrying-shaft adjacent to the initial disk of each set, spring latch-arms secured at one end to the face of each disk opposite that containing the apertures, a similar arm being similarly connected with each ratchet-wheel, each of the said latch-arms having a beveled foot-section formed at its free end, and posts on said foot-sections, adapted to enter apertures in opposing disks, fixed spurs located in the path of the foot-sections of the said latch-arms, a line-shaft common to both sets of disks, means for driving the line-shaft, eccentrics carried by the said line-shaft, and independent dogs carried by the said eccentrics, one dog being adapted for engagement with each ratchet-wheel.

3. In odometers, the combination with a casing, a carrying-shaft mounted for end and for rotary movement in the casing, a set of registering-disks loosely mounted on said shaft, a set of recording-disks likewise loosely mounted on the said shaft, the sets of disks being independent of each other, each disk having openings in one side face, a ratchet-wheel loosely mounted on the said shaft opposite the initial disk of each set, spring latch-arms attached to the faces of the disks opposite those provided with the openings and corresponding arms secured to the said disks, each latch-arm being provided with a beveled foot-

section at its free end and posts extending from the said foot-sections, and a bar located below the disks and provided with spurs which are in the path of the free ends of the latch-arms as the disks and ratchet-wheels revolve, of pins extending from the faces of the registering - disks having the openings therein, sleeves frictionally mounted on the shaft, each registering-disk being adapted to 10 turn loosely on a sleeve, each sleeve being provided with a finger to engage the pin of the disk to which it belongs, stops on the said shaft, whereby by moving the shaft endwise the disks are carried to and from the pin-

faces of the said registering-disks, a line- 15 shaft, cams carried by the line-shaft, means for rotating the line-shaft and dogs mounted on said cams, a dog being adapted for engagement with the ratchet-wheels of each set of disks, as described.

20 In testimony whereof I have signed my name to this specification in the presence of two subscribing witnesses.

BERNHARD VOLKMAR.
